(57) **CLAIM**

What is claimed is the ornamental design for a display panel of a programmed computer system with a graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a first view of a first embodiment of a display panel of a programmed computer system with a graphical user interface;

FIG. 2 is a second view thereof;

FIG. 3 is a third view thereof;

FIG. 4 is a fourth view thereof; and

FIG. 5 is a fifth view thereof;

FIG. 6 is a first view of a second embodiment of a display panel of a programmed computer system with a graphical user interface;

FIG. 7 is a second view thereof;

FIG. 8 is a third view thereof;

FIG. 9 is a fourth view thereof; and

FIG. 10 is a fifth view thereof.

The broken lines showing the display panel in FIGS. 6-10 form no part of the claimed design. The remaining broken lines showing portions of the graphical user interface form no part of the claimed design.

The appearance of the animated image transitions sequentially between the images shown in FIGS. 1-5 and 6-10 respectively. The process or period in which one image transitions to another forms no part of the claimed design.
